UNITED STATES PATENT OFFICE.

FRED H. CHAN, OF SAN FRANCISCO, CALIFORNIA.

DESIGN FOR A VEHICLE SIGNAL-LAMP CASING.

Application filed August 21, 1924. Serial No. 10,510. Term of patent 7 years.

To all whom it may concern:

Be it known that I, FRED H. CHAN, a citizen of the United States of America, residing at San Francisco, in the county of San Francisco and State of California, have invented a new, original, and ornamental Design for Vehicle Signal Lamp Casing, of which the following is a specification, reference being had to the accompanying drawing, forming a part thereof.

I claim:

The ornamental design for a vehicle signal lamp casing, as shown.

FRED H. CHAN.
